UNITED STATES PATENT OFFICE.

MARTIN J. FINNEGAN, OF NEW YORK, N. Y., ASSIGNEE TO ELEVATOR SUPPLIES COMPANY, INC., OF HOBOKEN, NEW JERSEY, A CORPORATION OF NEW JERSEY.

AUTOMATIC SCHEDULE REGULATOR FOR DISPATCHING SYSTEMS.

Application filed January 18, 1928. Serial No. 31,990.

This invention relates to dispatching systems and particularly to dispatching systems for elevators for use in buildings having a large number of elevators and considerable traffic. It is the object of this invention to provide as an additional feature of a system in which cars or other moving bodies are dispatched automatically in accordance with a predetermined schedule, means for adjusting and regulating the interval between the starting of the various cars and further to do this automatically, thereby eliminating the necessity of having one or more attendants for this purpose.

In this connection means are provided whereby when the traffic is light the cars will be dispatched on a comparatively slow schedule, and when the traffic is heavy the cars will be dispatched on a comparatively fast schedule; intermediate schedule speeds being provided, if desired, for intermediate degrees of traffic.

Specifically stated, when my novel apparatus is applied to the dispatching of elevators, it will produce this effect: When there are passengers waiting to be carried in either direction at an arbitrary number of floors, for example three or less, the cars will be dispatched with a certain predetermined interval (say, for example, 120 seconds) between the starting of successive cars; when there are passengers waiting to be carried in either direction at a number of floors ranging between 3 and 6, the cars will be dispatched with a smaller interval, say 100 seconds; when there are passengers waiting at a number of floors ranging from 6 to 9, the starting interval will be reduced to, say, 80 seconds; and so on, until a minimum starting interval (that is, a maximum schedule speed) is reached.

Thus it will be seen that the effect is to provide a flexible dispatching system which will automatically accommodate itself to the many changes in traffic conditions which commonly occur during the course of a day in the modern elevator-equipped buildings of any considerable height.

My invention consists in providing electrical apparatus for performing the work of the attendant so as to obtain an almost imperceptible flexibility and at the same time remove the human factor heretofore relied upon for adjusting the schedule.

My invention is capable of application to any of the well-known types of elevator signal systems (such as shown in patents to Smalley & Reiners, Numbers 634,220 and 826,752, and patents to Collett Numbers 634,229 and 700,619, issued respectively on Oct. 3, 1899, July 24, 1906, Oct. 3, 1899 and May 20, 1902). In fact it can be applied to any signal system wherein a push button or other passenger's signaling means is provided at each station or landing, together with means for causing a signal to be displayed in response to the pushing of such button or other signal means.

Other objects, features and adaptations will be made apparent as the description progresses, reference being had to the accompanying drawings, which show diagrammatically the parts comprising my novel apparatus.

In the drawings Figure 1 shows schematically my novel apparatus in connection with such parts of an ordinary signal system as are operated therewith. Figure 2 shows a portion of a common type of signaling mechanism to which my invention is readily applied. Fig. 3 shows a common type of car dispatching device.

In the drawing, reference character 1 designates an electric motor adapted to rotate at a predetermined constant speed, thereby operating thru contacts (shown in Fig. 3) starting and timing signals for the various cars in a predetermined sequence. The operation of timing signals thru a motor and contacts of this type is well known in the art, the more common types being shown in patents to Perine #9,998,034, Meyers #1,156,610 and Boardman #1,217,556.

In the armature circuit of motor 1 is the ordinary resistance unit 2 having a movable contact 3. The purpose of this resistance, of course, is to provide means for varying the speed of motor 1. At certain intervals along the resistance unit 2 are placed terminals 4, 5 and 6 to which conductors 7, 8 and 9 are connected for a purpose which will appear hereinafter.

Numerals 20 to 31 indicate contact devices, shown here as mercury pots, which, as will be seen by an inspection of Figure 2, are controlled by means of series of armatures, the armature for mercury pot 20 being shown at 14 in Figure 2. Armature 14 is as-

sociated with a magnet 15 which, when energized, attracts the same to withdraw contact 16 from the mercury. Magnet 17 has associated therewith an armature 18 which is 5 attracted by the energizing of magnet 17 but which normally is urged to the position shown in Figure 2 by spring 19. In this position it is obvious that armature 14 is locked out of contact making position by 10 armature 18. The circuit to magnet 17 is controlled by means of a push button, the contacts for which are indicated at 32 in Figure 2. This mechanism is well known in the art of signaling and is shown and de- 15 scribed in all of the signal patents mentioned above, particularly in the illustrations appearing in patent to Collett #700,619. However, in order to bring out the relation of this mechanism to my novel apparatus the 20 operation will be briefly described.

Buttons 32 and 33 are located on a floor past which the elevators are adapted to travel, it being understood that similar buttons and similar mechanism are provided for 25 each of the mercury pots shown in Fig. 1, there being one complete mechanism for each floor. When a passenger wishes to signal the elevators he presses the "up" or "down" push button, making one or the other of the contacts 32 and 33, according to the direction in which he desires to go. Closing of contacts 32 causes the energizing of magnet 17, which thereby attracts its armature, allowing armature 14 to descend by gravity, completing 30 a circuit thru the contact of finger 16 with the mercury. This circuit causes (either immediately or at a certain point in the routine running of some car) a signal to be displayed, usually a flashlight such as the one 35 indicated at 40 in Fig. 1, this being the signal that a passenger is waiting at the corresponding floor. Similarly such a signal is provided for each floor as indicated. So much of the mechanism is, as I have indicated, quite common in the art, consequently 45 further description will be dispensed with. My invention will now be described:

Connected in parallel with signals 40 to 50 51 are resistance units 60 to 71 respectively, so that whenever any of the signals 40 to 51 are displayed a circuit will also be made thru the corresponding resistance unit, as for example, a circuit from conductor 72, thru mercury pot 20, conductor 73, resistance unit 60, conductor 74, winding of relay 55 75, conductor 76, winding of relay 75, conductor 76, winding of relay 77, conductor 78, winding of relay 79, thence thru conductor 80 back to the other side of the line. Relays 60 75, 77 and 79 have associated therewith armatures 85, 87 and 89 normally held in the 65 position shown in Figure 1 by springs 95, 97 and 99 respectively. Each of these relays is adapted to attract its armature when a certain value of current is passed thru the

winding thereof. However the current necessary to enable relay 79 to attract its armature 89 is less than that necessary for relay 77 to attract its armature. Furthermore, the current necessary for relay 77 to attract its armature is less than that necessary for relay 75 to attract its armature, this condition being brought about, of course, by the manner of winding the various relays.

Let us suppose for example that the current necessary to cause relay 79 to attract its armature 89 against the tension of spring 99 is the sum of the currents passing thru resistances 60, 61 and 62 (or any other three resistance units), it being intended that all 75 of these units are of equal value. Let us further suppose that the current necessary for relay 77 to attract its armature is that passed thru six of these resistances connected as shown and that the current necessary to cause relay 75 to attract its armature is the current passed thru nine of these resistance units when circuits are made therethrough in the manner indicated. With this supposition in mind the 80 operation will be seen to be as follows:

Suppose passengers on the floors corresponding to mercury pots 20, 22 and 24 have pressed buttons signifying their intention to be picked up. Circuits will accordingly be made thru lamps 40, 42 and 44 in the manner heretofore described and also thru resistance units 60, 62 and 64. The result will be that the magnetic attraction set up in relay 79 will be sufficient 100 to attract its armature 89 thereby causing the circuit to the motor 1 to pass as follows:

Thru conductors 101 and 102, contacts made by armature 89, conductor 7, that portion of resistance unit 2 lying between contact 4 and contact arm 3, thence thru the armature winding and back to the other side of the line leading to a high voltage source of current. Before such attraction 110 of armature 89 took place, of course, the current thru armature passed thru the entire resistance unit as far as contact arm 3; consequently it will be obvious that when armature 89 closes the circuit just described, 115 that portion of the resistance lying between contact 4 and contact 10 will be cut out of the armature circuit and the speed of motor 1 will be increased by a certain predetermined amount, thereby causing the dispatching signals 110 and 111 operated by 120 said motor to be speeded up, the purpose being to cause more rapid movement of the cars than that which existed when there were fewer "waiting passenger" signals. Similarly let us suppose that all of the signals from 40 to 45 inclusive are now to be 125 operated. This will cause current to be passed thru each of the resistances 60 to 65 inclusive, which will bring the value of 130

the current passing thru winding of relay 77 to a value sufficient to cause the attraction of armature 87. This will cause the circuit to motor 1 to pass as follows:

5 Thru conductors 101, 103 and 104, contacts operated by armature 87, conductor 8, that portion of resistance 2 lying between contact 5 and contact arm 3, armature of 10 motor 1, thence back to the other side of the line. The effect will be to again reduce the amount of resistance in the armature circuit and again cause a speeding up of motor 1.

Now let us further suppose that nine or 15 more of the signals are placed in operating condition at one time. The result will be that not only armatures 87 to 89 will be attracted, but armature 85 will also be attracted, causing the circuit to motor 1 to 20 pass as follows:

Thru conductors 101 and 103, contacts operated by armature 85, conductor 89, that portion of resistance unit included between contacts 6 and contact arm 3, thence thru 25 armature 1 back to the other side of the line. In this manner a speed greater than any so far produced will be added, thereby necessitating a maximum speed on the part of the elevators in order to cope with the 30 increased traffic as indicated by the large number of "waiting passenger" signals. It will thus be seen that a dispatching system is produced which automatically accommodates itself to all conditions of traffic; it 35 being obvious that as the traffic decreases (as indicated by the canceling of the "waiting passenger" signals 40 to 51 due to the withdrawal of the associated mercury pot contacts) the reverse operations to those just 40 described will take place, and in the reverse order.

It is to be understood that when more than one of the contacts operated by armatures 85, 87 and 89 are made, the circuit to 45 motor 1 will pass thru the contact associated with the higher current relay, (just as described above) since the circuit traceable therethrough constitutes the path of least resistance.

50 In Fig. 3 I have shown a simple means of causing the operation of starting signals for the cars at predetermined intervals thru the instrumentality of a pair of contact makers 109 and 112 fixed to a disc which is 55 made to revolve slowly through suitable gearing to the motor 1. These contacts operate the starting bells 110 and 111. This particular embodiment is the invention of George H. Rowe, and is claimed by him in 60 Letters Patent No. 1,230,434, granted June 10, 1917, and serves very well to illustrate a conventional form of dispatcher, to which my invention is readily applied.

It is to be understood that various 65 changes may be made in the relative ar-

rangement, construction, and mechanical operation of the parts without departing from the spirit of my invention. Furthermore, while my automatic schedule regulating means will probably find its most apparent utility in connection with the dispatching of elevators, I do not limit myself to such application, as other uses and adaptations might readily occur to those skilled in the art of dispatching moving bodies.

Accordingly, I limit myself only by the scope of my invention as disclosed herein and as defined in the appended claims.

I claim:

1. In an elevator signalling system, a plurality of elevators, calling signals for each elevator, means controlled from the various floors for placing said signals in indicating condition, starting signals for said elevators, means for operating said starting signals in succession at predetermined intervals, means for varying the speed of said operating means and means for controlling said last named means so as to vary the speed of the operating means in proportion to the number of calling signals placed in indicating condition.

2. Apparatus as in claim 1, wherein the controlling means comprises a plurality of magnetic devices and means for operating said magnetic devices selectively each in dependence upon a different number of calling signals placed in indicating condition.

3. In an elevator signalling system, a plurality of elevators, calling signals for each elevator, means controlled from the various floors for placing said calling signals in indicating condition, starting signals for said elevators, means for operating said starting signals in succession at predetermined intervals comprising an electric motor, means for varying the speed of said electric motor comprising a plurality of excitation circuits for said electric motor, each including means to operate said motor at a different speed, and means for closing said excitation circuits selectively and in dependence upon the number of calling signals placed in indicating condition.

4. In an elevator signalling system, a plurality of elevators, calling signals therefor, means controlled from the various floors for placing said signals in indicating condition, starting signals for said elevators, means for operating said starting signals in succession at predetermined intervals, means for varying the speed of said operating means, and means for controlling said last-named means in accordance with the variation in the number of unanswered calling signals previously placed in indicating condition by the means herein set forth, said controlling means comprising means operated selectively each in dependence upon a different number of said floor controlled

means placed in operating condition, said means remaining in operation as long as said calling signals remain unanswered.

5. In an elevator signaling system, a plurality of elevators, calling signals therefor, means controlled from the various floors for placing said signals in indicating condition, starting signals for said elevators, means for operating said starting signals in succession at predetermined intervals, means for varying the speed of said operating means, and means for controlling said last-named means in accordance with the variation in the number of unanswered calling signals previously placed in indicating condition by the means herein set forth, said controlling means comprising a plurality of resistance units operable by the means for placing the calling signals in indicating condition, an electro-magnetic device in circuit with said resistance units, and means operable by said electro-magnetic device to actuate said speed varying means so as to effect a change in the speed of said signal operating means,
6. In an elevator signaling system, a plurality of elevators, calling signals therefor, means controlled from the various floors for placing said signals in indicating condition, starting signals for said elevators, means for operating said starting signals in succession at predetermined intervals, means

for varying the speed of said operating means, and means for controlling said last-named means in accordance with the variation in the number of unanswered calling signals previously placed in indicating condition by the means therein set forth, said controlling means comprising a plurality of electric circuits, a resistance unit in each circuit, another circuit connecting said last-named circuits, relay means operable upon the passage of a predetermined amount of current thru said connecting circuit to operate said speed varying means in response to the operation of a predetermined number of said resistance units.

7. Apparatus as in claim 6, wherein the means for varying the speed of said signal operating means comprises a plurality of excitation circuits, means in each of said excitation circuits for causing said signal operating means to operate at a speed different from the speed produced by the operation of any other of said excitation circuits, and wherein said relay means comprises a plurality of means each operable upon passage of a different predetermined amount of current through said connecting circuit to close one of said excitation circuits,

Signed at Hoboken, N. J. this 15th day of January, 1926.

MARTIN J. FINNEGAN.
